ATTORNEY.

UNITED STATES PATENT OFFICE.

CHARLES W. BOOTH, OF GREENVILLE, OHIO.

PULVERIZING ATTACHMENT FOR PLOWS.

Application filed March 18, 1927. Serial No. 176,390.

This invention relates to pulverizing attachments for plows and more particularly to a device so mounted on the plow that it will engage the furrow slice in the rear of the mold board and break the same into small pieces.

One object of the invention is to provide such a device which may be mounted on the beam and supported independently of the mold board; and which will be of a strong durable character.

A further object of the invention is to provide such a device which may be so adjusted with relation to the beam as to support the pulverizing element in the desired position.

15 A further object of the invention is to provide in such a device a pulverizing element the parts of which will be adjustable relatively one to the other and which will be adjustable as a whole with relation to the supporting member.

Other objects of the invention will appear as the device is described in detail.

In the accompanying drawings Fig. 1 is a front elevation of a portion of a plow showing my invention applied thereto; Fig. 2 is a side elevation of a device embodying my invention; Fig. 3 is a top plan view of the same; Fig. 4 is an elevation of the supporting frame of the pulverizing element; and 30 Figs. 5 and 6 are detail views of this supporting frame.

In these drawings I have illustrated one embodiment of my invention but it will be understood that this particular embodiment 35 has been chosen for the purpose of illustration only and that the apparatus may take various forms without departing from the spirit of the invention.

40 In the particular construction here illustrated the apparatus comprises a pulverizing element indicated as a whole by the reference numeral 10. This pulverizing element comprises a plurality of pulverizing fingers, or soil engaging bars, 11, in the present instance three, which are rigidly secured to a supporting frame 12 which is arranged in an upright position so that the pulverizing fingers will be supported one above the other and spaced apart. The supporting frame 12 may be of any suitable construction, and may either be cast or be formed from sheet metal. The particular supporting frame here illustrated is formed from sheet metal and to facilitate the manufacture thereof, as well as to provide additional adjustments, it is formed in two parts. One of these

parts, 13, is substantially U-shaped in construction and has laterally extending portions or brackets 14 extending in the same direction therefrom and substantially parallel one with the other. The other part of the supporting frame, 15, is substantially Z-shaped and has parts or brackets 16 extending therefrom in opposite directions. One of these brackets 16 extends substantially parallel with the adjacent bracket 14 of the other part of the frame and is rigidly secured thereto so that the frame as a whole comprises a rigid structure. The pulverizing bars 11 are secured to the laterally extending portions or brackets 14 and 16 of the frame and because of the arrangement of these brackets with relation one to the other the pulverizing bars will be out of vertical alinement. Preferably the pulverizing bars are adjustable with relation to the frame to enable them to be positioned at different angles with relation thereto and, further, the bars are adjustable with relation one to the other so that they may, if desired, be caused to extend at different angles. The character of the adjustable connections between the frame and the pulverizing bars may take various forms and will in a measure depend upon the character of the frame. In the present instance, where the frame is of the sheet metal construction above described, the supporting portions or brackets 14 and 16 of the frame are provided with arcuate slots 17 through which extend the bolts 18 by means of which the bars are secured to the brackets. The bars are supported on the outer surfaces of the brackets so that they will have a relatively wide range of adjustment with relation thereto. Preferably the intermediate pulverizing bar 11 is supported between the adjacent brackets 14 and 16 of the two parts of the frame and the bolts 18 which connect this bar with the brackets also serves to connect the two parts of the frame one to the other.

100 The pulverizing element 10 is carried by a supporting member or bar 19, the rear end of which is rigidly secured to the frame 12 and the forward end of which is provided with means for attaching the same to the beam 20 of the plow. As here shown, this attaching means is in the form of a bracket 21 rigidly secured to the beam and preferably this bracket is in the form of a clamp to engage the beam so that it may be secured thereto without forming holes in the beam or otherwise weakening the same and may be se-

cured to the beam in different positions. The supporting bar is so mounted on the bracket that it will extend rearwardly therefrom adjacent to the upper edge of the mold board 22 of the plow and will support the pulverizing element behind this mold board with the fingers projecting inwardly beyond the same at such an angle thereto that they will engage the furrow slice which is turned over by the 10 mold board. The connection between the supporting member 19 and the bracket 21 is preferably a pivotal one so that the pulverizing element may be moved toward or from the mold board. As here shown, the bracket 21 15 extends some distance to the rear of the beam and is provided with a bearing 23 which, in the present instance, comprises a clip rigidly secured to the bracket. This bearing is arranged at an inclination to the vertical and 20 has mounted therein a rod 24. The upper end of this rod projects some distance above the bracket and the forward end of the connecting bar 19 is pivotally mounted thereon, preferably by means of a bolt 25 extending 25 through the bar and through the rod. In the present instance, a reinforcing member or strap 26 is secured to the supporting bar and overlaps the upper portion of the rod to receive that end of the bolt 25 opposite the bar 19 and thus provide a firm support for the bolt, or pivot pin. The lower end of the rod 24 extends below the bracket 21 and a brace bar 27 is connected at one end with the lower portion of the rod and at the other end with 30 the connecting bar 19. The connection between the brace bar 27 and connecting bar 19 is an adjustable one so that the connecting bar and pulverizing element may be vertically adjusted. As here shown, the connecting bar 35 has a series of openings 28 each adapted to receive a bolt 29 by means of which the brace bar is connected to the connecting rod. By attaching the brace bar to the connecting bar at different points the vertical position of the connecting bar may be changed. The rear 40 end of the connecting bar 19 may be secured to the pulverizing element in any suitable manner but the connection is preferably an adjustable one so that the supporting frame 45 12 may extend at different angles with relation to the connecting bar. As here shown, one part of the supporting frame, the part 13, is provided in its vertical portion with arcuate slots 30 to receive the bolts 31 by means of 50 which the connecting bar is secured to the supporting frame.

The pulverizing element is preferably connected with the plow beam by a draft device which is separate from the supporting member 19. As here shown, the frame 12 of the pulverizing element has secured thereto a lug or bracket 32, which may be attached to the frame by the bolts 31 by means of which the supporting bar 19 is connected therewith. 55 Extending through this bracket 32 is a short

rod 33 which is provided with a nut 38 in the rear of the bracket 32 to limit its forward movement with relation thereto. At its forward end the rod 33 is connected with a chain 34, the forward end of which is attached to the beam so that the chain and the rod 33 will constitute the draft device and will receive the major portions of the strains to which the pulverizing element is subjected. The chain may be connected with the beam in various ways but, in the present device, the bracket 21 has a rearwardly and outwardly extending arm 35 which is rigidly secured thereto and which has in its rear end an opening to receive one of the links of the chain 34, as shown at 36. A pin 37 extends through the link and serves to lock the same in the opening in the arm 35. The length of the draft device may be varied by connecting different links with the arm 35. The pin 37 is of such a character that it will support the normal strains to which the pulverizing element is subjected but will yield or be sheared off when the pulverizing element is subjected to abnormal strains, as when it strikes a 90 stone or other obstruction through which it cannot pass, thus releasing the draft device and permitting the pulverizing element to move away from the mold board and pass the obstruction without causing injury to other parts of the apparatus.

The operation of the apparatus will be readily understood from the foregoing description of the several parts thereof and it will be apparent that I have provided a device of such a character that the pulverizing fingers will engage the furrow slice immediately in the rear of the mold board and will pulverize the same, that is, will break the same into relatively small pieces. The extent of the pulverization or the breaking up of the furrow slice will depend, of course, in a measure, on the character and condition of the soil. The pulverizing element and its supporting draft devices are of such a character that the soil engaging bars may be arranged in a position most suitable for the particular plow or the particular soil with which the device is being used. The device as a whole is simple in its construction and of such a character that it can be manufactured at a relatively low cost.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. A pulverizing attachment for plows comprising a pulverizing element, a supporting member therefore, a bracket having means for connecting the same with the beam of a plow, means for adjustably con-

necting said supporting member with said bracket, and a draft device separate from said supporting member for connecting said pulverizing element with said beam and retaining the same normally in fixed relation thereto.

2. A pulverizing attachment for plows comprising a pulverizing element, a supporting member therefor, means for pivotally connecting said supporting member with the beam of a plow to permit said pulverizing element to move toward or from the mold board of said plow, and a draft device to connect said pulverizing element with said beam and cause said pulverizing element to move with said plow in a substantially fixed position with relation to said mold board.

3. A pulverizing attachment for plows comprising a pulverizing element, a supporting member therefor, means for pivotally connecting said supporting member with the beam of a plow to permit said pulverizing element to move toward or from the mold board of said plow, a draft device to connect said pulverizing element with said beam and cause said pulverizing element to move with said plow in a substantially fixed position with relation to said mold board, and means for vertically adjusting said supporting member and said pulverizing element.

4. A pulverizing attachment for plows comprising a pulverizing element, a supporting member therefor, a bracket having means for securing the same to the beam of a plow, means for pivotally connecting said supporting member with the bracket to permit said pulverizing element to have movement toward and from the mold board of said plow, and a draft device to connect said pulverizing element with said beam and hold said pulverizing element normally against movement from said mold board.

5. A pulverizing attachment for plows comprising a pulverizing element, a supporting member therefor, a bracket having means for securing the same to the beam of a plow, means for pivotally attaching said supporting member to said bracket to permit said pulverizing element to move toward and from the mold board of said plow, and a draft device to connect said pulverizing element with said beam and retain the same normally in fixed relation thereto, the connection between said draft device and said beam being separable under excessive strains.

6. A pulverizing attachment for plows comprising a pulverizing element, a supporting member therefor, a bracket having means for securing the same to the beam of a plow, means for pivotally attaching said connecting member with said bracket to permit said pulverizing element to move toward and from the mold board of said plow, a draft chain connected at one end with said pulverizing element, a part carried by said beam

and having an opening to receive a link of said chain, and a pin extending through said link to secure the same to said beam.

7. A pulverizing attachment for plows comprising a pulverizing element, a supporting member therefor, a bracket having means for securing the same to the beam of a plow, means for pivotally attaching said connecting member with said bracket to permit said pulverizing element to move toward and from the mold board of said plow, a draft chain connected at one end with said pulverizing element, a part carried by said beam and having an opening to receive a link of said chain, and a pin extending through said link to secure the same to said beam, said pin being of such strength that it will support the normal strains to which said pulverizing element is subjected but will yield under excessive strains on said pulverizing element.

8. A pulverizing attachment for plows comprising a pulverizing element, a supporting bar secured at one end to said pulverizing element, a bracket having means for securing the same to the beam of a plow, an upright rod rotatably mounted on said bracket for movement about a longitudinal axis, means for pivotally connecting said supporting bar with said rod on a substantially horizontal axis, means for holding said bar normally against movement about said horizontal axis, and a draft device to connect said pulverizing element with said beam.

9. A pulverizing attachment for plows comprising a pulverizing element, a supporting bar secured at one end to said pulverizing element, a bracket having means for securing the same to the beam of a plow, a rod rotatably mounted on said bracket for movement about an upright axis, means for pivotally connecting said supporting bar with said rod on a substantially horizontal axis, a brace bar connected with said rod, means for adjustably connecting said brace bar with said connecting bar to support the latter in different positions with relation to said rod, and a draft device to connect said pulverizing element with said beam.

10. In a pulverizing attachment for plows, a pulverizing element comprising a frame, a plurality of soil engaging bars secured to said frame, and adjustable thereon, a connecting member secured to said frame, means for supporting said connecting member on the beam of a plow, and a draft device to connect said supporting frame with said beam.

11. In a pulverizing attachment for plows, a pulverizing element comprising an upright frame, a plurality of soil engaging bars adjustably secured to said frame and extending transversely thereto, a connecting member for said frame, means for adjustably securing said connecting member to said supporting frame to permit the latter to extend

at different angles with relation to said connecting member, means for supporting said connecting member on the beam of a plow, and a draft device to connect said supporting frame with said beam.

12. In a pulverizing attachment for plows, a pulverizing element comprising an upright frame having laterally extending portions, a part of said portions projecting from one side of said frame, and a part from the other side thereof, soil engaging bars rigidly secured to the respective lateral portions of said frame, and means for connecting said pulverizing element with the beam of a plow.

13. In a pulverizing attachment for plows, a pulverizing element comprising an upright frame having a plurality of laterally extending portions, a plurality of soil engaging bars supported by the respective laterally extending portions of said frame, means for adjustably securing said bars to said laterally extending portions of said frame, and means for connecting said pulverizing element with the beam of a plow.

14. In a pulverizing attachment for plows, a pulverizing element comprising an upright frame formed in two parts, each of said parts having laterally extending portions, a plurality of soil engaging bars supported by the laterally extending portions of said frame, means for rigidly securing said bars to said laterally extending portions and for securing the two parts of said frame one to the other, and means for connecting said pulverizing elements with the beam of a plow.

15. In a pulverizing attachment for plows, a pulverizing element comprising a frame consisting of a U-shaped portion and a Z-shaped portion, the adjacent parts of the two portions of said frame being arranged substantially parallel one with the other, soil engaging bars supported by the lateral parts at the outer ends of the two portions of said frame, another soil engaging bar supported between the adjacent parts of the two portions of said frame, means for rigidly securing said soil engaging bars to the respective portions of said frame and for securing the two portions of said frame one to the other, and means for connecting said supporting frame with the beam of a plow.

16. In a pulverizing attachment for plows, a pulverizing element comprising a supporting frame having laterally extending portions each of which is provided with arcuate slots, pulverizing bars supported by the respective laterally extending portions of said frame, bolts extending through said bars and the respective arcuate slots, a connecting bar, means for adjustably securing said connecting bar to said supporting frame, a bracket having means for rigidly securing the same to the beam of a plow, means for mounting said connecting bar on said bracket, and a draft device connecting said frame with said bracket.

In testimony whereof, I affix my signature hereto:

CHARLES W. BOOTH.
